UNITED STATES PATENT OFFICE.

CHARLES P. BREESE, OF DAYTON, OHIO.

FIELD ENGINE STARTER.

Application filed February 17, 1921. Serial No. 445,665.

To all whom it may concern:

Be it known that I, CHARLES P. BREESE, a citizen of the United States, residing at Dayton, in the county of Montgomery and State 5 of Ohio, have invented certain new and useful Improvements in Field Engine Starters, of which the following is a specification.

This invention relates to field engine starters, the object in view being to produce portable means of a practical nature adapted to start aeronautical engines, and especially the engines of airplanes.

It will be understood that at aviation fields or centers, a large number of machines are employed and said machines are usually of various types and sizes so that the engines and propellers are located at different distances from the ground level, and furthermore—the angles of the engine and propeller shafts vary greatly. It is therefore necessary, in the production of practical field engine starters, to provide means—quickly and easily adjustable—whereby the driving power of the starting mechanism may be applied directly to the propeller shaft for the purpose of imparting rotary motion thereto. This is particularly important in cold weather, much time being lost and great danger being involved under the present method of cranking propellers by hand.

With the above general object in view, the invention consists in the novel construction, combination and arrangement herein fully described, illustrated and claimed.

35 In the accompanying drawings:

Fig. 1 is a side elevation of the field engine starter, showing the working relation thereof to the propeller shaft of an aeronautical engine;

40 Fig. 2 is an end view thereof taken at a right angle to Fig. 1;

Fig. 3 is an enlarged, vertical, longitudinal section through the starter;

Fig. 4 is a vertical section taken at a right angle to Fig. 3, showing the driving means between the motor and the starter shaft;

Fig. 5 is a horizontal section taken just

below the elevator looking downwardly and showing the elevating means;

Fig. 6 is a fragmentary, longitudinal section showing the means for sliding the base of the apparatus; 50

Fig. 7 is a perspective view of the recessional clutch-head;

Fig. 8 is an enlarged, longitudinal section 55 thru the clutch head showing a portion of the starter shaft in elevation.

Under the preferred embodiment of the invention, the field engine starting mechanism is mounted upon and adapted to be moved from place to place by a wheeled truck, designated generally at "A". The body or platform 10 of said truck has an opening 11 therein surrounded by an up-standing combing 12, thus forming a cockpit for the starting mechanism. Arranged in the cockpit are parallel track rails 13, having longitudinal slots 14 in the upper sides thereof to receive headed bolts or runners 15 which extend downwardly from a slidible supporting base 16, said base being in the form of an open rectangular frame with re-enforced corner blocks 17, each containing a nut 18.

Passing through the nuts 18, four in number, are vertical elevating screws 19, the upper ends of which are connected by bevel gears 20 and 21 to counter-shafts 22, so that all of the elevating screws 19 may be simultaneously and equally rotated for the purpose of raising and lowering the elevating platform 23 which is supported on the upper ends of said screws. The hand wheel 24 on one of the counter-shafts 22 provides means for imparting motion to the elevating mechanism. 85

The slideable base 16 is actuated by means of a sprocket chain 25, which passes around sprocket wheels 26 on shafts 27 at the front and rear ends of the cockpit, the opposite end 90 portions of said sprocket chain passing under said sprocket wheels being fixedly secured at 27 to the opposite end bars of said slideable base. One of the shafts 26 has a

ratchet wheel 29 thereon, which in conjunction with a ratchet lever 30 enables the shaft 26 to be rotated, thereby shifting the slidable base in one direction or the other. The slid-
5 able arrangement just referred to, taken in connection with the elevating means, forms a part of the means for adjusting the starter shaft, hereinafter described, into actual alignment with the engine shaft, as will
10 hereinafter appear.

The elevating platform supports what is in effect a universal joint, illustrated generally at "B", the same comprising a lower bowl-shaped or concavo-convex member 31 secured to the elevating platform 23 by fastening means 32, and an upper bowl-shaped or concavo-convex member 33 which fits into the lower member 31. The members 31 and 33 are formed with central openings to receive the shank of a clamping member 34, which may be tightened or loosened for the purpose of clamping or unclamping the upper member 33. This enables the mechanism supported upon the upper member 33 to be turned to another angle or tilted to any direction and to any degree for the purpose of aligning the starter shaft with the engine or propeller shaft.

Supported upon the upper member 33 is a rectangular frame 35 and extending upward therefrom and rigidly fastened thereto are bearing brackets 36, two of such brackets being shown and being braced longitudinally by braces 37. Journaled in the 30 bearings of the brackets 36 is starter shaft 38, which shaft is also slidable longitudinally in said bearings, the latter being indicated at 39.

Shaft 38 is driven by means of a motor 40 (an electric motor being shown), the shaft 40 of said motor carrying a pinnion 41. The pinnion is meshed into a gear 42 journaled on the counter-shaft, the latter having a sprocket wheel 43 from which a chain 44 extends upwardly and around a large sprocket wheel 45, having a non-circular opening thru which a non-circular portion 46 of the starter shaft 38 is slidable. The wheel 45 is held against moving with the shaft 38 by means of a thrust bearing 47 on one of the brackets 36.

A sprocket chain and wheel guard 48 is employed to protect the sprocket gearing.

The starter shaft 38 is shiftable longitudinally through the bearings 39 and the wheel 45 by means of a thumb-latch lever 49, the latch 50 of which engages an arcuate rack 51 secured fixedly to the frame 35. The swiveled connection 52 is provided between the lever 49 and the shaft 38 to allow for the sliding movement of the latter. A storage battery 53 is shown as mounted upon and supported by the frame 35, the energy thereof being utilized to actuate the electric motor 40. A suitable switch is provided for the purpose of throwing the elec-

tric motor in and out of operation. Mounted upon the projecting end of the starter shaft 38 is a clutch head, designated generally at "C". Said clutch head comprises a face or clutch-plate 54, having a plurality of holes or notches 55 to receive and engage the usual nuts or bolt heads on the propeller hub or, in other words, the bolts—by means of which the propeller is fastened to the propeller flange of the propeller shaft. The 75 clutch-plate 54 has on its rear side lugs 56, each of which is secured by fastening means 57 to one end of one of a series of springs or spring-plates 58. The other end of each spring is secured by fastening means 59 to the adjacent end of one of a series of spider arms 60, extending from a hub 61, internally threaded and engaging one or more steeply pitched threads 62 on the shaft 38.

Extending rearwardly from the hub 61 are other spider arms 63, having secured thereto a hand wheel 64 which is made of sufficient weight to counter-balance the weight of the clutch-plate 54 and the parts adjacent thereto. This prevents the clutch-head as a whole from tilting and binding on the shaft 38. The hand wheel 64 enables the clutch-head to be advanced by a rotative movement into position to engage the nuts on the propeller hub, the final engagement being obtained by thrusting lever 49 toward the propeller hub until the nuts on the propeller hub enter the bolts or notches 55. When the aircraft engine starts, it rotates at a speed greater than the speed of the starter shaft 38; and consequently, the clutch head is caused to recede away from the propeller hub by means of threads 62 which engage the internally threaded hub 61. The recessional movement of the clutch head is yieldingly arrested or cushioned by means of a coiled buffer spring 65, which lies behind the hub 61 and surrounds the shaft 38 and is backed up by a stop collar 66 adjustably secured to the shaft 38 by fastening means 67, such as one or more set screws. The springs 58 yieldingly hold the face-plate 54 against the propeller hub and also allow for any inaccuracy of alignment between the starter shaft 38 and the propeller shaft of the airplane.

In operation, the wheeled truck is driven to a position in front of the airplane so that the wheel of the truck stand at a right angle to the wheels of the landing gear of the airplane. The starting mechanism is then swung laterally with respect to the truck, as shown in Figure 1. By means of the elevating mechanism, hereinabove described, the frame 35 is then adjusted to the proper elevation. The sliding base is then moved to bring the starter shaft into the plane of the propeller shaft. By means of the universal connection between the frame 35 and the elevating mechanism, said

frame 35 is then tilted to the proper angle and the universal joint is clamped against further movement. By the means just referred to, the starter shaft 38 is brought into 5 actual alignment with the propeller shaft. The clamping head "C" is then moved toward the end of the shaft 38 after which, by means of the lever 59, face-plate 54 is thrust into engagement with the nuts on the 10 propeller hub. This adjustment is maintained by means of the latch 50 engaging the rack 51. The switch controlling the electric motor is then closed, imparting motion to the starting shaft 38 and cranking the propeller shaft. As soon as the airplane engine takes up its cycle of operation, the 15 excess of speed thereof over the speed of the starter shaft 38 causes a recessional movement of the clutch-head which backs away 20 from the propeller hub and disconnects the starting mechanism from the hub of the airplane propeller. The truck carrying the starting mechanism may then be driven to the next place of operation.

25 One of the most important features of the invention hereinabove described is the mounting of the starter shaft and the actuating motor thereof on one and the same supporting frame, which frame is capable 30 of being raised and lowered, turned and tilted to any degree necessary to place the starter shaft in actual alignment with the propeller shaft. This allows the mechanism of the whole to be brought into proper 35 actuating relation to the propeller shafts of the various types and kinds of aircraft now in use.

I claim—

40 1. An engine starter embodying in combination, a supporting base, a superposed platform, shaft bearings fixedly secured to said platform, an engine starting shaft journaled in said bearings, a starting motor mounted on said platform for driving said starting shaft, and means for adjusting the height of said platform in relation to the supporting base.

45 2. An engine starter embodying in combination, a supporting base, a superposed platform, shaft bearings fixedly secured to said platform, an engine starting shaft journaled in said bearings, a starting motor mounted on said platform for driving said starting shaft, and means for adjusting the angle of said platform in relation to the supporting base.

50 3. An engine starter embodying in combination, a supporting base, a superposed platform, shaft bearings fixedly secured to said platform, an engine starting shaft journaled in said bearings, a starting motor mounted on said platform for driving said starting shaft, and means for tilting said platform to change the angle of the starting shaft.

4. An engine starter embodying in combination, a supporting base, a superposed platform, shaft bearings fixedly secured to said platform, an engine starting shaft journaled in said bearings, a starting motor mounted on said platform for driving said starting shaft, and a universal joint between said platform and the supporting base. 70

5. An engine starter embodying in combination, a supporting base, a superposed platform, shaft bearings fixedly secured to said platform, an engine starting shaft journaled in said bearings, a starting motor mounted on said platform for driving said starting shaft, a universal joint between said platform and the supporting base, and clamping means to hold said joint rigid. 75

6. An engine starter embodying in combination, a supporting base, a superposed platform, shaft bearings fixedly secured to said platform, an engine starting shaft journaled in said bearings, a starting motor mounted on said platform for driving said starting shaft, a universal joint between said platform and the supporting base, and platform elevating means. 80

7. An engine starter embodying in combination, a supporting base, a superposed platform, shaft bearings fixedly secured to said platform, an engine starting shaft journaled in said bearings, a starting motor mounted on said platform for driving said starting shaft, and means for shifting said shaft as a whole longitudinally. 95

8. In a field engine starter, a motor-driven engine starting shaft, and a clutch head on said shaft embodying a clutching member, and cushioning means between said clutching member and said shaft serving to press the clutch head towards its work. 100

9. In a field engine starter, a motor-driven engine starting shaft, a clutch head thereon, and threaded means for causing a positive recessional movement of the clutch head on said shaft when the speed of the engine shaft exceeds the speed of the starting shaft. 110

10. The combination of a supporting base, a platform adjustable in relation to said base, an engine starting shaft journaled in fixed bearings on said platform, and a motor mounted on said platform in driving connection with said shaft. 115

11. The combination of a supporting base, a platform universally adjustable in relation to said base, an engine starting shaft journaled in fixed bearings on said platform, and a motor mounted on said platform in driving connection with said shaft. 120

12. The combination of a supporting base, a platform adjustable in relation to said base, an engine starting shaft journaled in fixed bearings on said platform, a clutch head movable longitudinally of said starting shaft, and a motor mounted on said platform in driving connection with said shaft. 125

13. The combination of a supporting base, a platform adjustable in relation to said base, an engine starting shaft journaled in fixed bearings on said platform, a recessional clutch head on said starting shaft, and a motor mounted on said platform in driving connection with said shaft. 70
14. The combination of a supporting base, a platform adjustable in relation to said base, an engine starting shaft journaled in fixed bearings on said platform, a recessional clutch head on said starting shaft, manually operable means for setting said clutch head in working position, and a motor mounted on said platform in driving connection with said shaft. 75
15. The combination of a slidable supporting base, a platform adjustable in relation to said base, an engine starting shaft journaled in fixed bearings on said platform, a clutch head movable longitudinally of said starting shaft, and a motor mounted on said platform in driving connection with said shaft. 80
16. The combination of a supporting base, a platform adjustable in relation to said base, an engine starting shaft journaled in fixed bearings on said platform, and a motor mounted on said platform in driving connection with said shaft, said supporting base being slidable in such manner as to enable the starting shaft to be shifted laterally. 85
17. The combination of a supporting base, a platform adjustable in relation to said base, an engine starting shaft journaled in fixed bearings on said platform, a resilient clutch head movable longitudinally of said starting shaft, and a motor mounted on said platform in driving connection with said shaft. 90
18. The combination of a supporting base, a platform adjustable in relation to said base, an engine starting shaft journaled in fixed bearings on said platform, a counterbalanced clutch head movable longitudinally of said starting shaft, and a motor mounted on said platform in driving connection with said shaft. 95
19. An engine starter embodying in combination, a supporting base, a superposed platform, shaft bearings fixedly secured to said platform, an engine starting shaft journaled in said bearings, a starting motor mounted on said platform for driving said starting shaft, means for shifting said shaft as a whole longitudinally, and means for locking said starter shaft against longitudinal movement. 100
20. In a field engine starter, a base, and a motor-driven rotary starting shaft rigidly supported in bearings fixed to said base, said base being adjustable to align said shaft with the propeller shaft of an aircraft. 110
21. In a field engine starter, a base, and a motor-driven rotary starting shaft rigidly supported in bearings fixed to said base, said base being adjustable to align said shaft with the propeller shaft of an aircraft. 115
22. In a field engine starter, a base, a rotary starting shaft rigidly supported in bearings fixed to said base, a motor mounted on said base and arranged to drive said starting shaft, and means for adjusting said base to align said shaft with the propeller shaft of an aircraft. 120
23. In a field engine starter, a base, a rotary starting shaft rigidly supported in bearings fixed to said base, and having means to engage the engine shaft, a motor mounted on said base and arranged to drive said starting shaft, and means for adjusting said base to align said shaft with the propeller shaft of an aircraft. 125
24. The combination with a motor vehicle, of a power driven device for starting the engine of an aeroplane comprising a motor, a cranking shaft, means for detachably connecting the cranking shaft with the propeller of the aeroplane, means for operatively connecting the cranking shaft with the motor, and means for adjusting the cranking shaft, motor and connecting means to engage the cranking shaft with the aeroplane propeller. 130
25. The combination with a vehicle, of a power driven device for starting the engine of an aeroplane comprising a motor, a cranking shaft, means for detachably connecting the cranking shaft with the propeller of the aeroplane, means for operatively connecting the cranking shaft with the motor, and means for adjusting the cranking shaft, motor and connecting means to engage the cranking shaft with the aeroplane propeller. 135
26. In an aeroplane launching device, the combination with an aerial propeller, of a rotatable member adapted to engage said propeller, means for adjusting said member substantially longitudinally of the propeller axis, and means for adjusting it laterally and also vertically relatively to said axis, all of said adjustments being manually operated from a common point remote from the point of application of said member. 140
27. In an aeroplane launching device, the combination with an aerial propeller, of a rotatable member adapted to engage said propeller, means for adjusting said member substantially longitudinally of the propeller axis, and means for adjusting it laterally and also vertically relatively to said axis, all of said adjustments being manually operated from a common point remote from the point of application of said member. 145
28. In an aircraft engine starting device, the combination of a supporting base, a support adjustable in relation to said base, an 150

engine starting shaft journaled in bearings on said support, and a motor mounted on said support in driving connection with said shaft.

29. In an aircraft engine starting device, the combination of a supporting base, a support adjustable in relation to said base, an engine starting shaft journaled in fixed bearings on said support, and a motor mounted on said support in driving connection with said shaft.

30. An aircraft engine starter embodying

in combination, a supporting base, a superposed support, shaft bearings fixedly secured to said support, an engine starting shaft 15 journaled in said bearings, a starting motor mounted on said support for driving said starting shaft, and means for adjusting the support in relation to the supporting base and in a vertical plane.

In testimony whereof I have affixed my signature.

CHARLES P. BREESE.
